UNITED STATES PATENT OFFICE.

TITUS S. INGRAHAM, OF CLEVELAND, OHIO.

DESIGN FOR AN ADVERTISING-CARD.

SPECIFICATION forming part of Design No. 26,309, dated November 17, 1896.

Application filed August 24, 1896. Serial No. 603,779. Term of patent 14 years.

To all whom it may concern:

Be it known that I, TITUS S. INGRAHAM, a citizen of the United States, and a resident of Cleveland, county of Cuyahoga, and State 5 of Ohio, have invented and produced a new and original Design for an Advertising-Card, of which the following is a specification, reference being had to the accompanying drawing, forming part thereof.

10 The leading feature of my design is the surface ornamentation shown in the drawing and consisting principally of a horizontal bar intercepted by a circular figure, the said bar being ornamented by two eight-lobed figures, 15 one on each side of said circular figure. The circular figure consists of a plane circle bor-

dered by four symmetrical figures consisting principally of concentric arcs of circles drawn from the center of the plane circle, the middle of said figures being each ornamented by 20 an eight-lobed figure.

What I claim, and desire to secure, is—
The design for an advertising-card, as herein shown and described.

In testimony that I claim the foregoing to 25 be my invention I have hereunto set my hand this 21st day of August, A. D. 1896.

T. S. INGRAHAM.
